Robert L. Weber III, 19 Judson Court,
Huntington, Conn.

Filed Apr. 27, 1960, Ser. No. 60,344

Term of patent 14 years

(Cl. D16—2)

FIG. 3

FIG. 4

FIG. 1 is a front perspective view of an electrically heated liquid vaporizer for dispensing smells or the like embodying my new design.

FIG. 2 is a top plan view.

FIG. 3 is a rear elevational view.

FIG. 4 is a bottom plan view.

FIG. 5 is a detail view of a portion of the inner cylinder showing one of the star like ornaments on an enlarged scale.

FIG. 6 is a sectional view taken on the line 6—6 in FIG. 5.

The dominant features of my design reside in the full line portions of the drawing.

I claim:

The ornamental design for an electrically heated liquid vaporizer for dispensing smells or the like, as shown and described.
